CLAIM

The ornamental design for a split heel set for a bar gun handle assembly, as shown and described.

DESCRIPTION

FIG. 1 is a perspective view of a split heel set for a bar gun handle assembly, shown in an assembled manner, showing our new design;

FIG. 2 is an exploded unassembled view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is an in-use exploded perspective view thereof, shown unassembled for connection with a bar gun; and,

FIG. 10 is a perspective view of the split heel set for a bar gun handle assembly, shown assembled with a bar gun.

The broken line showing of a bar gun is included for the purpose of illustration and forms no part of the claimed design.
